DESIGN FOR AN AIRPLANE WING

James Henry Schley, Jr., Alabama City, Ala.

Application September 18, 1934, Serial No. 53,316

Term of patent 14 years

To all whom it may concern:

Be it known that I, James Henry Schley, Jr., a citizen of the United States, residing at Gadsden, in the county of Etowah and State of Alabama, have invented a new, original, and ornamental Design for Airplane Wing, of which the following is a specification, reference being had to the accompanying drawing, forming part thereof:

In the drawing:

Fig. 1 represents a rear end elevation of the wing.

Fig. 2 represents a top plan view of the wing.

Fig. 3 represents a front end elevation of the wing.

Fig. 4 represents a sectional view through line "A" "A" shown on Fig. 2, all showing my new design.

I claim:

The ornamental design for airplane wing, as shown.

JAMES HENRY SCHLEY, JR.
